DEVICE FOR AUTOMATIC STITCHING OF
CARDBOARD BOXES

Olof Einar Larsson, Orebro, Sweden

Application August 17, 1949, Serial No. 110,818
In Sweden January 11, 1946

7 Claims. (Cl. 1—11)

1

This invention relates to machines for stitching together pieces of material and more particularly to such a machine as can be conveniently adjusted for automatically stitching pieces of cardboard and boxes of various sizes.

The machine of the present invention provides for starting a stitching operation by contact of a forward edge of pieces of material to be stitched together with a member which initiates a stitching operation which is automatically terminated after a selected number of clips have been set in the course of stitching a seam along the material. Provision is made for changing the number of clips which may be placed or set during any one stitching operation, for changing the intervals between clips, for determining how far from the forward edge of the material the first clip of a series of clips is to be set, and for locating the material laterally of the line of clips. Accordingly, it is possible to begin and stop a stitching operation at predetermined locations in the material and in materials of different widths and lengths, and in rows having any number of clips desired.

The invention is illustrated in the accompanying drawings in which

Fig. 1 is an elevational view of the front or feeding side of the machine;

Fig. 2 is a rear elevational view of the machine;

Fig. 3 is a view taken from the right end of Fig. 1;

Fig. 4 is an enlarged view of the divisional or variable ratio apparatus illustrated in Fig. 1;

Fig. 5 is a view of the divisional apparatus as seen from the right of Fig. 4;

Fig. 6 is a detail of a controlling shaft through which a stitching operation is initiated;

Fig. 7 is a face view of the one-way driving clutch illustrated in section in Fig. 4; and

Fig. 8 is a finger wheel with pivoted fingers.

The machine comprises a frame supporting a table 1 over which the sheets of cardboard or other material pass during a stitching operation. The sheets are fed forwardly over a table and between a pair of rollers 6 and a feeding roller 12, Fig. 1, which extends through a longitudinal slot in the table 1. The roller 12 is mounted upon a shaft 5 which is journaled in bearings which are located under the table. The shaft 5 is driven from the shaft 4, Fig. 2, by a belt. The drive for the shaft 4 is obtained from a change speed mechanism or variator 31 which is driven from a motor driven pulley 25 by means of a chain or sprocket connection.

2

The outer longitudinal edges of the sheets which are to be stitched together are engaged by a pair of endless belts 2 which are advanced by pulleys 3 which are mounted upon vertical shafts. The surfaces of the endless belts 2 which face each other may be parallel, but preferably they are pitched with respect to each other so that the sheets between them are laterally justified.

The vertically disposed pulleys 3 are driven from the shaft 4 through pairs of bevel gears 43, one of each pair of gears 43 being slotted to engage and slide along a spline in the shaft 4. The upper bevel gear 55 of the pair of bevel gears 43 (at the right end of Fig. 2) is mounted on a vertical shaft of one of the pulleys 3 by which the edgewise justifying bands 2 is driven. The vertical shafts of the pulleys 3 and the horizontal shafts 56 of the rollers 6 are mounted on a slideable carriage 57. The shaft of the handwheel 40 carries a bevel gear which meshes with a bevel gear on a shaft having a worm connection with the carriage 57. The spacing of the pairs of bevel gears 43 and of the endless bands 2 may be adjusted by the handwheel 40 for suitably positioning the bands to accommodate the particular width or box size of the sheets of material which are to be fed and stitched together. Since the speed of rotation of the shaft 4 can be varied with respect to the speed of rotation of the motor driven pulley 25 by adjusting the variator 31, and the pulley 25 drives the stitching controlling shaft 46 when the latter is coupled to the pulley, it is apparent that the velocity of the belts 2 and the rate of rotation of the feed roller 12 may be changed to vary the spacing between successive clips.

One clip is set by the stitching apparatus 44 for each revolution of the shaft 46 which operates the stitching apparatus. The shaft 46 is journaled in bearings supported by the stitching head 24 which extends from one end of the frame of the machine laterally across and above the table. The stitching apparatus 44 is of conventional form and the stitching is performed in the usual manner with metal bands or wire. Shaft 46 is driven intermittently from the motor driven pulley 25, which is coupled to the shaft 46 each time a series of stitching clips is to be set.

A stitching operation is started by a rotary motion of the shaft 7 which is horizontally disposed above the table 1, Figs. 2 and 3. The same shaft 7 is illustrated on an enlarged scale in Figs. 5 and 6. The rotation of shaft 7 causes the shaft 46 to be coupled to the motor driven pulley 25. The shaft 7 has mounted thereon a wheel 8 which

carries four pivoted fingers 52, Figs. 2 and 6, by which the shaft 7 can be rotated in only one direction. Each finger is of such length that when it extends downwardly toward the table it will be engaged and displaced by the forward edge of the sheets of material being advanced over the table, with the result that the advancing sheets will rotate shaft 7 a quarter of a revolution and that being possible because of the fact, that the next finger (52a in Fig. 8) is lifted by the advancing sheet until it has passed, when the finger swivels into position (52b) for meeting the forward edge of a new sheet. Each quarter of a revolution initiates a stitching operation. The shaft 7 carries a cam wheel 23 having four projections or wipers 23' corresponding to the four fingers 52 on wheel 8. As the shaft 7 is rotated a quarter of a revolution by the advance edge of the sheets to be stitched together, a corresponding wiper 23' engages a wing 45 on the shaft 9 and rocks the shaft 9 clockwise as viewed in Figs. 1 and 4, and counterclockwise as viewed in Figs. 2 and 6, to the position 45b. A crank 11 is mounted upon the forward end of the shaft 9, Figs. 1 and 5. The crank 11 is pivotally connected to a link 10, which in turn is connected to a double crank 51 whose upper arm is connected to a movable clutch collar of a clutch by which the motor driven pulley 25 is coupled to the shaft 46. Consequently, each time the shaft 9 is rocked clockwise, as viewed in Figs. 1 and 4, the operation of the stitching apparatus is initiated. This occurs as a result of the quarter-rotation of shaft 7 which is caused by the advancing edge of the material to be stitched, as explained hereinabove. The shaft 46 continues to rotate until the selected number of clips have been placed, and when this happens the rock shaft 9 is restored to its normal position, Figs. 1 and 4.

The duration of rotation of the shaft 46 and hence the number of clips which are set for one seam, is controlled by the number of actuations required for the disk 22 to make one complete revolution. When the shaft 9 is first rocked at the initiation of a stitching operation, the lever 27, as best seen in Fig. 4, is rocked clockwise by the link 10 and moves the rod 26 to the left against the action of the spring 49. The rod 26 carries a roller 48 which is seated in a dwell 50 in the flange of the disk 22 when the machine is at rest, Fig. 4. The disk 22 is intermittently advanced in one direction through a ball or roll coupling 47, that is, a one-way clutch, and the first rotary movement of disk 22 occurs when the operation of the shaft 46 is started. This happens when the roller 48 is withdrawn from the dwell 50 by the rocking of the lever 27 when a stitching operation is initiated. Thereafter and until the disk 22 has made one complete revolution, the roller 48 rides upon the flange of the disk 22 and maintains the rod 26, the lever 27, the rock shaft 9 and the double crank 51 in their rocked positions. When the disk 22 has completed a full revolution the roller 48 is again able to enter the dwell 50. As this occurs the shaft 46 is disengaged from the motor driven pulley 25, and the stitching operation immediately ceases.

The disk 22 is part of the variable ratio or division apparatus whereby the number of clips to be set during each stitching operation is determined. The division apparatus is best shown in Figs. 4 and 5. One clip is set for each revolution of the shaft 46 and the disk 22 is advanced a fraction of a revolution for each revolution of

shaft 46. The division apparatus is driven from the shaft 46 by a chain and sprocket connection 15 which drives the shaft 13 at a ratio of one to one.

The shaft 14 is driven from shaft 13 by a linkage which is adjustable for oscillating the shaft 14 a fraction of a revolution for each revolution of the shaft 13, depending upon the selected ratio of rotation between the two shafts 13 and 14. 10 The inner portion of the one-way clutch 47 is fast on shaft 14 and causes the disk 22 to be advanced in one direction a distance equal to the amplitude of oscillation of the shaft 14 each time shaft 13 makes a complete revolution.

15 The mechanism by which the shaft 14 is driven by shaft 13 and by which the ratio of rotation between the two shafts may be varied, includes a variable radius crank comprising a screw 17 which is carried by a member or wheel 16 which is mounted upon shaft 13. The axis of the screw 17 passes through the axis of the shaft 13 and is mounted in brackets so as to be rotatable to change the position of a nut 18 radially of the member 16. The nut 18 is non-rotatable and carries a crank pin 18' which can be positioned any selected distance from the axis of shaft 13 by rotating the screw 17. The shaft 14 carries a wheel 21 upon which is mounted a crank pin 20. A connecting rod 19 serves as a link between the crank pin 18' and the crank pin 20. The wheel 21 and the shaft 14 is given an amplitude of movement equal to twice the radius of the crank pin 18', or $2r$, each time the crank pin 18' makes one complete revolution due to slippage 30 of the one way clutch during the second half revolution of the wheel 16. The nut 18 of the crank pin 18' may be positioned anywhere along the screw which will provide a ratio which is divisible into the circumference of the path of travel of the crank pin 20 an equal number of times, such, for example, as 3, 5, 12 and 20. A scale with divisions indicating the possible positions of the crank pin 18' for obtaining desired ratios is conveniently applied alongside of the screw 18, as shown in Fig. 5.

As explained hereinbefore, the duration of rotation of the shaft 46 and hence the number of complete revolutions of the shaft 46 and of the wheel 16 is determined by the number of actuations of the disk 22 which are required to rotate the disk 22 through 360° . For example, since one clip is set for each revolution of the wheel 16, the wheel 16 will have to make five complete revolutions to advance the disk 22 one complete revolution with the center of the crank pin 18' positioned opposite the No. 5 graduation, as shown in Fig. 5. When five clips have been set, the wheel 16 will have made five revolutions and the disk 22 will have made one complete revolution. 55 At the completion of the single revolution of the disk 22, the roller 48 on rod 26 enters the dwell 50 on the disk 22 and thereby causes the double crank 51 to rock and disengage shaft 46 from the motor driven pulley 25 and thereby terminate the stitching operation.

It is apparent that the shorter the radial arm of the crank pin 18', the greater the number of revolutions of the wheel 16 will be required before the disk 22 has completed one full revolution, and vice versa. With the crank pin 18' located at any one of the positions, 3, 5, 12 and 20 of the scale, the disk 22 will rotate 120° , 72° , 30° and 18° , respectively for each full revolution of the wheel 16, so that with the crank pin 18' at 70 one of the positions 3, 5, 12 and 20, the wheel 16

will rotate three, five, twelve and twenty complete revolutions, respectively, for each complete revolution of the disk 22, and 3, 5, 12 or 20 clips will be set, depending upon the position in which the crank pin 48 has been set.

In order that the disk 22 may not follow disk 21 during its return stroke of its oscillation, a brake 28 is provided which slides against the periphery of the disk 22 until the roller 48 falls into the notch 53. At the moment this occurs, the brake 28 enters the notch 53 in the rim of the disk 22. The relationship of the notch 53 and of the brake 28 is such that small adjusting movements of the wheel 22, which may occur when the roller 48 enters the notch 53, are permitted. At the same moment the lever 27 causes the shaft 9 and the double crank 51 to free the shaft 46 from the pulley 25 and bring the machine to a standstill. The brake 28 is influenced by a soft spring and is so adjustable that it is very lightly pressed against the rim of the disk 22, which therefore stands still when it is not moved forward by the disk 21 and the one way clutch 47. When the brake 28 is opposite the notch 53 and an advancing motion comes from the rod 19, the brake will slide onto the rim of the disk 22 without being hindered in an appreciable degree by the light brake pressure.

The location of the first clip from the edge of a sheet or sheets of material is determined by the distance between the stitching apparatus 44 and the shaft 7 as measured along the surface of the table 1. The shaft 7 is suspended from a shaft 30 which carries two gears 58 and 59 resting upon a pair of racks 29 which extend horizontally from the frame of the machine. By rotating the handwheel 54 on shaft 30 the shaft 30 may be moved towards or away from the stitching apparatus 44 so as to locate the shaft 7 at the distance from the stitching apparatus which is to correspond with the distance of the first clip in a seam from the forward edge of sheets of material which are to be stitched together.

In Fig. 2 there is illustrated a pair of endless bands 12' which have reaches extending over the surface of the table 1. These endless bands are driven by the shaft 4 and may supplement or be used in place of the roller 12 for advancing the sheet material over the table. The sheet material is pressed against the travelling surfaces of the bands by the rollers 6. The spacing of the bands 12' may be changed as desired by rotating the handwheel 40.

This application is a continuation-in-part of my application Serial No. 763,967, filed July 26, 1947.

What is claimed is:

1. In a device of the class described, stitching apparatus for setting clips into sheets of material, a shaft for driving said stitching apparatus, a source of power for actuating said shaft, coupling means for coupling said source of power and said shaft during a stitching operation, and means operable by the material to be stitched for controlling said coupling means for coupling said source of power and said shaft, said controlling means including a rotatable shaft and a finger wheel mounted thereon, said finger wheel including a plurality of fingers adapted to extend, one at a time, according to the rotary position of said finger wheel shaft, into the path of the advance edge of material to be stitched.

2. In a device of the class described, stitching apparatus for setting clips into sheets of material, a shaft for driving said stitching apparatus,

a source of power for actuating said shaft, coupling means for coupling said source of power and said shaft during a stitching operation, means for controlling said coupling means for coupling said source of power and said shaft, said controlling means including a rotatable shaft and a finger wheel mounted thereon, said finger wheel including a plurality of fingers adapted to extend, one at a time, according to the rotary position of said finger wheel shaft, into the path of the advance edge of material to be stitched, means for feeding material to be stitched into engagement with a depending finger of said finger wheel to cause the finger wheel to rotate a fraction of a revolution at a time for starting a stitching operation, and mechanism driven from said source of power for driving said material-feeding means.

3. In a device of the class described, stitching apparatus for setting clips into sheets of material, a shaft for driving said stitching apparatus, a source of power for actuating said shaft, coupling means for coupling said source of power and said shaft during a stitching operation, means for controlling said coupling means for coupling said source of power and said shaft, said controlling means including a rotatable shaft and a finger wheel mounted thereon, said finger wheel including a plurality of fingers adapted to extend, one at a time, according to the rotary position of said finger wheel shaft, into the path of the advance edge of material to be stitched, means for feeding material to be stitched into engagement with a depending finger of said finger wheel to cause the finger wheel to rotate a fraction of a revolution at a time for starting a stitching operation, and mechanism driven from said source of power for uncoupling said driving shaft from said source of power, said motion-transmitting mechanism including a ratio changing device which is settable for uncoupling said driving shaft when it has completed a predetermined number of revolutions.

4. In a device of the class described, stitching apparatus for setting clips into a sheet of material, a shaft for driving said stitching apparatus, a source of power for driving said shaft, a rotatable controlling shaft, a wheel carried by said controlling shaft, said wheel having fingers extending, one at a time, into the path of material to be stitched, means for feeding said material past said stitching apparatus and into contact with one of the fingers of said wheel, means controlled by the rotation of said finger wheel shaft for coupling said driving shaft and said source of power to start a stitching operation when the material fed by said feeding means is fed thereby into contact with a finger on said finger wheel, a pair of racks extending parallel to the direction of feed of the material being fed, gears engaging the said racks, a shaft extending between said gears, means carried by said last-named shaft for rotatably supporting said controlling shaft whereby said controlling shaft and finger wheel may be moved longitudinally of said racks to position said finger wheel with respect to said stitching mechanism to locate the first clip of a series of clips at a desired distance from the advance edge of the material to be stitched.

5. In a device of the class described, stitching apparatus for setting clips into sheets of material, a shaft for driving said stitching apparatus, a source of power for driving said shaft, a rotatable shaft carrying a wheel having fingers extending, one at a time, into the path of ma-

terial to be stitched, conveyor means for feeding said material into contact with one of the fingers of said finger wheel for rotating said finger wheel and rotatable shaft a fraction of a revolution at a time, means controlled by said last-named shaft for coupling said source of power to said first-named shaft for starting a stitching operation, and a pair of endless belts mounted on vertical axes and spaced apart for justifying the longitudinal edges of the material to be stitched as the material is fed into contact with said finger wheel and under said stitching apparatus.

6. In a device of the class described, stitching apparatus for setting clips into sheets of material, a shaft for driving said stitching apparatus, a source of power, conveyor means for feeding the material to said stitching apparatus, said conveyor means being mounted on horizontal axes and having surfaces gripping the opposite surfaces of the material adjacent the marginal edges of the material, means connecting said conveyor means with said source of power, a pair of endless belts mounted on vertical axes for guiding the edges of the material as it is being fed, a rotatable controlling shaft, a wheel mounted on said controlling shaft, said wheel having fingers extending, one at a time, into the path of material being fed by said feeding means, means operable by said controlling shaft for coupling said source of power and said first-named shaft for starting a stitching operation,

and means driven from said source of power for uncoupling said first-named shaft from said source of power when a predetermined number of clips have been set.

- 5 7. In an apparatus of the class described, stitching apparatus for setting clips into sheets of material, a shaft for driving said stitching apparatus, a source of power for actuating said shaft, means for coupling said source of power and said shaft during a stitching operation, means for feeding material to be stitched, means operable by the material being fed for controlling said coupling means for coupling said source of power and said shaft, means operable to uncouple said shaft from said source of power at the conclusion of a stitching operation, said last-named means comprising a dividing apparatus for determining the duration of operation of said shaft and said stitching apparatus and including a crank driven by said shaft, a second crank driven by said first crank, adjustable means between said first crank and said second crank for changing the ratio of the rates of rotation between said two cranks, a rotatable 20 disc, a one-way clutch between said second crank and said disc for intermittently advancing said disc, and means controlled by said disc for uncoupling said first-named shaft from said source of power.
